POINT FOR A CORN PICKER GATHERING
SHOE

Ivan P. Schmid, Columbus, Nebr.

Application May 1, 1950, Serial No. 9,609

Term of patent 14 years

(Cl. D40—1)

To all whom it may concern:

Be it known that I, Ivan P. Schmid, a citizen of the United States and a resident of Columbus, in the county of Platte and State of Nebraska, have invented a new, original, and ornamental Design for a Point for a Corn Picker Gathering Shoe, of which the following is a specification, reference being had to the accompanying drawing, forming part thereof.

Figure 1 is the top view, and Figure 2 is the side view, of a point for a corn picker gathering shoe, showing my new design.

I claim:

The ornamental design for a point for a corn picker gathering shoe, as shown.

IVAN P. SCHMID.
